Bosch Aktiengesellschaft, Stuttgart, GermanyApplication April 23, 1932, Serial No. 607,194
In Germany April 28, 1931

6 Claims. (Cl. 123—140)

The present invention relates to centrifugal governors for internal combustion engines, more especially solid injection Diesel motors, which are designed to prevent a maximum speed being exceeded as well as to prevent the speed of the motor dropping below a minimum speed. The object of the invention is to improve on the centrifugal governors hitherto employed.

One example of construction of a governor according to the invention is illustrated in the accompanying drawings, in which:

Figure 1 is a longitudinal sectional view of the governor with its operating rods, a partial elevational view of a fuel pump with which the governor is shown as used, and pedal-operated mechanism for an adjustment of the fuel control member of the pump in addition to the governor adjustment.

Figure 2 a sectional view of the bearings of the eccentric shaft in the governor casing.

Figure 3 is a perspective view of the eccentric shaft and associated parts showing a lever connected with the governor sleeve.

The centrifugal governor is mounted on the conical stub *a* of the shaft of the fuel pump, and secured by means of a locked nut or the like. The governor consists of a governor body *b*, which carries on its periphery two centrifugal weights *c*. These weights stand under the influence of two springs *d*₁ and *d*₂, the tensions of which are designed to correspond to the extent of control required for running idle and under full load respectively. The initial compressions and consequent tensions of the governor springs can be adjusted by adjustable spring plates *e*. The relatively weak springs *d*₁ engage between the adjustable spring plates *e* and the bottoms of the weights *c*, so that the springs *d*₁ are always operative on the weights but the relatively strong springs *d*₂ engage between the spring plates *e* and apertured spring plates *u* loosely mounted on the stay bolts and engaging fixed collars on those bolts, as shown in Fig. 1, so that the stronger springs *d*₂ do not begin to operate on the weights until the idling speed has been exceeded and the weights have moved radially outward sufficiently for their apertured bottoms to clear the collars on the bolts and engage the spring plates *u*. Each governor weight is connected by a bellcrank lever, which for the sake of clearness is only indicated in Fig. 1 in broken lines, to the axially guided cross pin or bolt *f*. This cross-pin is connected with the governor sleeve *i* by a slide *g* which is axially guided in the bush *h*, and to this sleeve is pivoted the two-armed lever *k* by means of a pivot block *l*.

The two-armed lever *k* is revoluble on an eccentric disc *m*, the axis of which is mounted in bearing bushes *n*₁, *n*₂ screwed from the outside in the wall of the governor casing. To the upper arm of the two-armed lever *k* is connected the connecting rod *p* which connects the governor with the controlling rod *q* of the fuel pump.

A casing *o* encloses both the governor as well as the transmission parts between the governor and the controlling rod *q* of the pump in such a manner as to be dust-and water-tight. The casing is divided in such a way that after taking off the cover the whole of the transmission members are freely accessible from all sides. A flexible sleeve *r* is inserted in the space between the point where the coupling rod *p* emerges from the governor casing and the guide for the controlling rod *q* so as to enclose said space.

As Figure 2 shows, a lever *t* is fastened on the eccentric shaft *s* outside the governor casing *o*, to which lever the rod of the fuel pedal is connected.

The governor device hereinbefore described and shown in the drawings works as follows:

When the engine is running idle, in which case the fuel pedal is in the position shown, that is, at rest, then the centrifugal weights *c*, under the slight compression of the governor springs *d*, intended for running light, fly out to a small extent, whereby the controlling rod *q* is so adjusted through the parts *f*, *g*, *i*, *l*, *k*, *p*, that the fuel pump only feeds as much fuel as is necessary for the maintenance of the low engine speed. As the speed when running light increases, the throw of the centrifugal weights increases and the governor sleeve is drawn to the right. The two-armed lever *k* is thereby turned about the eccentric disc *m* as the fixed pivot point and moves the regulating rod *q* to the left, that is in the closing or stopping direction. The injection of fuel is diminished and thus the engine speed becomes lower.

By stepping on the fuel pedal, the eccentric disc *m* is rotated by the rods connected with it and the lever *t* to such an extent that the lever *k* displaces the controlling rod *q* to the right, that is, into the opening, or accelerating direction. In this voluntary adjustment the pins serving for the pivotal connection of the pivotal block *l* and the two-armed lever *k* thus form the fixed axis of rotation.

If the fuel pedal is depressed more strongly or for a longer period corresponding to the load on the engine, the speed of the engine increases, and thus the energy of the centrifugal weights *c*

increases in such a way that it overcomes the strong governor springs d_2 , and moves the governor sleeve to the right, whereby an adjustment of the controlling rod g is effected in the closing or decelerating direction.

Of course, the various parts can be otherwise constructed and arranged; thus, for example, instead of the governor being arranged on the shaft of the fuel pump it may also be arranged on the 10 engine (not shown). Furthermore, if desired, the connecting rod p could be arranged to be adjustable in length, so that at a certain position of the governor the suitable position of the controlling rod g of the fuel pump, that is to say, for 15 the corresponding quantity of fuel sprayed in, can be adjusted. Also the invention is not limited to a certain form of the centrifugal weights. Finally, it is optional to connect that arm of each 20 bellcrank lever which is directed towards the axis of the governor directly with the governor sleeve i , and the latter may then be arranged axially displaceable on a shaft end.

Preferably, however, the various parts are arranged as shown in the drawings as certain advantages arise from that arrangement. The 25 apertures in the casing walls, through which the bearing bushes n_1 n_2 extend are, as shown in Fig. 2, of such diameter as to allow passage of the eccentric m as well as the shaft s there- 30 through in assembling the parts. As also shown in Fig. 1, the casing is a two-part or divided casing with a rear portion, to the right in Fig. 1, and a front portion or cover. This arrangement not only provides a dust and moisture proof cas- 35 ing about the governor and its connections with the fuel-control member of the pump, but also enables the pump with all the governor parts to be initially assembled as a whole and attached as a unit to the engine, and likewise as a unit 40 disengaged from the engine for inspection and adjustments, repairs or replacement.

The disclosed arrangement also presents cer- 45 tain advantages in assembly of the governor and its operating connections, and access thereto for inspection and adjustments. In the assembly, the inner casing portion, to the right in Fig. 1, may first be mounted on the exterior flange of the pump as shown in that view, and then the 50 governor body or hub b secured on the projecting end a of the pump shaft and the weights mounted in position and the springs adjusted. Before the 55 cover portion of the casing is placed in position, the governor is thus sufficiently exposed for the ready connection thereto of the remaining parts. The bell crank levers may then be connected to the 60 fly weights c and to the cross pin or bolt f , the governor sleeve i mounted on the end of the slide g and the latter threaded through the bush- 65 ing h and the bushing secured in place on the governor body, the floating lever k pivotally mounted on the governor sleeve i through the pivot block l , and the upper end of that lever connected, through link rod p , to the fuel control rod q of the pump. Then all that remains 70 to be done, is the placing of the cover portion of the casing in position, with one of the bushings n_1 n_2 in its sides removed, and the endwise insertion through the exposed aperture and 75 through the hub portion of the lever k (see Fig. 3) of the shaft s with the eccentric m thereon until the far end of the shaft extends into the bearing aperture of the opposite bushing and the eccentric m is properly located in the hub por- 80 tion of the lever k , and finally, the external pedal

rod is connected, by the arm t , Fig. 2, to the end of the shaft s projecting from one side of the governor casing.

We declare that what we claim is:

1. A speed regulator for solid injection internal combustion engines comprising an adjustably movable fuel control member, a floating lever mechanically connected to said fuel control member for adjustably moving the same, manual means for voluntarily operating said lever to adjust the fuel supply, said means being connected at a point on said lever spaced from the connection between said lever and said fuel control member, and a centrifugal governor connected at another point on said lever spaced from said first-mentioned point and adapted to control the fuel supply to prevent the engine speed from rising above a given maximum value and from descending below a given minimum value, said lever being adapted to pivot about an axis passing through either one of its points of connection to said manual and centrifugal controls according to the operation of said controls. 85

2. A speed regulator for solid injection internal combustion engines comprising the combination, 100 with a fuel pump having a movably adjustable fuel control member and a shaft projecting beyond the pump casing, of a floating lever mechanically connected to said fuel control member and having a journal bearing spaced from 105 said connection, a manually displaceable control member, a rotatable shaft connected to said manually displaceable control member, an eccentric on said shaft journalled in said bearing formed in said lever, and a centrifugal governor 110 mounted on the projecting end of said pump shaft and driven thereby and connected to said lever at a point displaced from the bearing for said eccentric.

3. A speed regulator for solid injection internal 115 combustion engines comprising the combination, with a fuel pump having a movably adjustable fuel control member and a pump shaft projecting outwardly of the pump casing, of a governor mounted on the outer end portion of said pump 120 shaft and driven thereby, a removable casing supported by said pump casing about the outwardly projecting portion of said pump shaft and entirely enclosing said governor, connection means wholly within said casing operatively connecting said governor with said fuel control member for movement of said member, and means for voluntarily adjusting said fuel control member comprising a shaft rotatably journalled in side walls of said casing, manually operable means 125 detachably connected to said shaft outside said casing for turning said shaft, and an element on said shaft within said casing operating on said connection means to adjustably move said control member independently of said governor. 135

4. A speed regulator for solid injection internal combustion engines comprising the combination, with a fuel pump having a movably adjustable fuel control member and a pump shaft projecting outwardly of the pump casing, of a governor 140 mounted on the outer end portion of said pump shaft and driven thereby, means connecting said governor with said fuel control member comprising a lever having a journal bearing intermediate its length and means connecting one end of said lever to said governor and the other end of said lever to said control member, a removable casing supported on said pump casing about the outwardly projecting portion of said pump 145 150

shaft and enclosing said governor, lever and connecting means, a shaft rotatably journaled in side walls of said casing and an eccentric on said shaft engaging in said lever bearing, and manually operable means detachably secured to said shaft outside said casing for turning said shaft.

5 5. A speed regulator as in claim 4 and in which said casing is provided with aligned openings in opposite walls thereof adapted to receive bearings for said rotatable shaft, said openings being sufficiently large for the endwise insertion therethrough into operative relation with said lever within the casing of said shaft with said eccentric thereon.

10 15. 6. A speed regulator for solid injection internal combustion engines comprising an adjustably movable fuel control member, a floating lever mechanically connected to said fuel control member for adjustably moving the same, manually actuated mechanism and a centrifugal governor so connected to said lever at points spaced from

each other and from the connection of said lever to said fuel control member as to render said mechanism operable to move said lever about the point of connection thereto of said governor as a pivot and said governor operable to move said lever about the point of connection thereto of said mechanism as a pivot, said mechanism being adapted upon actuation to move said control member through said lever to adjust the fuel supply for the entire range of engine speeds from idling to full load running and said governor having centrifugal-weight and spring means operating on said control member through said lever at idling and full load running to prevent the engine speed from rising above a given maximum value for idle running and above a given maximum value for full load running and inoperative on said control member at an intermediate range of speed.
